(57) **CLAIM**

The ornamental design for a valve, as shown and described.

DESCRIPTION

1. Valve

1.1 : Top

1.2 : Bottom

1.3 : Front

1.4 : Back

1.5 : Right

1.6 : Perspective

Left side view is omitted because it is identical to the right side view; only the parts indicated in solid lines are the features requiring the design protection.

The broken lines are for the purpose of illustrating portions of the valve and form no part of the claimed design.
